Specification for Design.

Patented July 15, 1919.

Application filed April 5, 1919. Serial No. 287,827. Term of patent 3½ years.

To all whom it may concern:

Be it known that I, JAMES H. BUNTING, a citizen of the United States of America, residing at Clifton, in the county of Passaic, State of New Jersey, have invented a certain new, original, and ornamental Design for a Brocade, of which the following is a specification, reference being had to the accompanying drawing, forming a part thereof.

The figure is a plan view of a piece of brocade, showing my new design.

I claim:

The ornamental design for a brocade as shown.

In testimony whereof I hereunto affix my signature.

JAMES H. BUNTING.
